Primary Examiner—Jeffrey Asch
Attorney, Agent, or Firm—Perman & Green, LLP[57] **CLAIM**

The ornamental design of a key matrix for a telephone handset, as shown and described.

DESCRIPTION

FIG. 1 is a front elevational view of a key matrix for a telephone handset showing our new design;

FIG. 2 is a bottom, right side perspective view thereof; and, FIG. 3 is a top, left side perspective view thereof.

The broken lines showing of the front of a telephone handset is for illustration purposes only and forms no part of the claimed invention.
